CLAIM

I claim the ornamental design of a beverage flute, as shown and described.

DESCRIPTION

FIG. 1 is a front perspective view of a beverage flute showing my new design;

FIG. 2 is a bottom perspective view of the beverage flute of FIG. 1;

FIG. 3 is a left side view of the beverage flute of FIG. 1;

FIG. 4 is a right side view of the beverage flute of FIG. 1;

FIG. 5 is a rear view of the beverage flute of FIG. 1;

FIG. 6 is a front view of the beverage flute of FIG. 1;

FIG. 7 is a top plan view of the beverage flute of FIG. 1; and,

FIG. 8 is a bottom plan view of the beverage flute of FIG. 1.

The broken lines in the drawings depict portions of the beverage flute that form no part of the claimed design.
